UNITED STATES PATENT OFFICE.

JOSEPH FELLOWS, OF PHILADELPHIA, PENNSYLVANIA.

FOOD-SLICER.

SPECIFICATION forming part of Letters Patent No. 680,032, dated August 6, 1901.

Application filed December 7, 1899. Serial No. 739,539. (No model.)

To all whom it may concern:

Be it known that I, JOSEPH FELLOWS, a citizen of the United States, residing in Philadelphia, Pennsylvania, have invented certain 5 Improvements in Machines for Slicing and Shaving Food, of which the following is a specification.

My invention relates to certain improvements in machines for slicing or shaving food. 10 My invention is especially adapted for shaving dried beef and other meats and cutting bread.

The object of my invention is to simplify the working parts of the machine and to provide 15 feed mechanism which can be adjusted so as to shave the beef to any thickness desired.

In the accompanying drawings, Figure 1 is a plan view of my improved food slicing or 20 shaving machine. Fig. 2 is a side view. Fig. 3 is an end view. Fig. 4 is a sectional view on the line 4 4, Fig. 1. Fig. 5 is a detail view showing the knife-shaft and its bearings. Fig. 6 is a sectional view showing the friction 25 feed mechanism. Fig. 7 is a section on the line 7 7, Fig. 6. Fig. 8 is a section on the line 8 8, Fig. 7. Fig. 9 is a perspective view of the pawl-carrier of the friction-feed. Fig. 10 is a perspective view of the shifting-pin 30 for the pawl-carrier. Fig. 11 is a view of the feed-lever, and Fig. 12 is a modification of the pawl-carrier-shifting pin.

A is the frame of the machine, having in the present instance a trough A', which is 35 supported at its outer end by a foot a. The frame A is preferably of the shape shown clearly in Fig. 3, being flanged and forming a casing around the cutting mechanism, also having a foot a'.

A² is a cover-plate which is hinged to the frame A at a² and is held to the frame by a latch a⁴, which passes in front of a lug a⁵ on the cover-plate, so that by turning this latch back the cover-plate can be readily moved on 45 its hinge, so that access can be had to the interior of the casing.

B is the knife-shaft of the machine. This shaft is adapted to a suitable bearing b in the casing and the bearing b' on the bracket b². 50 On the outer end of this shaft is a handle B', by which the shaft is turned. Mounted on the shaft b is an arm B², carrying the knife-

blade B³. In the present instance there is only one arm and one knife-blade; but it will be understood that two or more knife-blades 55 may be used without departing from my invention.

It will be noticed that the cover-plate A² rests between the handle B' and the knife-carrier B² and is recessed at a³, the recess extending to the shaft. By this construction the knife is inclosed; yet the cover-plate can be moved on its pivot or entirely removed without detaching the handle.

The shaft B has a screw-threaded portion, 65 and on the screw-threaded portion are two nuts c c'. The nut c bears against the cam G and has a set-screw c², and the nut c' bears against the bearing b' and has a set-screw c³, so that on adjusting these nuts on the shaft 70 any wear of the knife-blade or of the bearings can be taken up, since the shaft can be moved longitudinally thereon and locked in any position desired. By simply backing off the set-screws and the screw that holds the 75 cam G to the shaft the shaft can be entirely withdrawn from the machine for the purpose of repairing or removing the knife, if necessary.

The knife is curved and shears past the end 80 of the trough A' of the frame, so that when the beef or other food is fed forward in the trough it will be sliced by the knife, and the sliced portions will fall onto the table on which the machine is mounted or through an 85 opening in the table into a suitable receptacle, if desired.

In order to feed the material forward uniformly, so that the slices will be properly cut, I mount on the fixed shaft D, Fig. 2, a pusher 90 E, having a box e, through which the shaft D extends. Extending also through this box e is a feed-rod F, which is reciprocated, and friction mechanism is provided, so that when the rod F is reciprocated the pusher E will be 95 moved intermittently forward.

The cam G on the shaft B acts against one arm h of a lever H. (Shown clearly in Fig. 11.) This lever is pivoted at h' to the frame of the machine, and on the lever is a set-screw 100 h², which strikes against the frame and limits the movement of the lever in one direction. The long arm h³ of the lever has a pin, which engages a collar f on the rod F, so that as the

cam is revolved by the shaft B it forces the short arm of the lever out and draws the rod F toward the head of the machine, causing the pusher to move forward. A spring h^4 , 5 which is coiled around the pivot h' , presses against the rear of the arm h^3 of the lever and tends to force the rod back. Thus the roller on the end of the arm h of the lever is kept in contact with the cam.

10 In order to vary the movement of the rod F, a set-screw h^2 is used, which strikes the casing, limiting the rearward movement of the rod. By turning this screw either forward or backward the amount of movement of the rod 15 is regulated, and thus the feeding mechanism for feeding the material toward the knife can be set in any desired position and the slices cut can be any thickness desired.

The friction-feed mechanism I prefer to use 20 is clearly shown in Figs. 6, 7, 8, 9, and 10.

In the box e of the pusher E are two tapered sockets e' e^2 , through which pass the rod F and shaft D, respectively. Mounted 25 within the sockets and on the rod F and shaft D is a carrier I, having recesses i on each side of the rod F, and adapted to these sockets are balls i^2 , which rest within the tapered socket e' and in the carrier I. On each side of the shaft D are recesses i' , in which rest 30 balls i^3 .

Mounted on the rod F is a washer k , and back of the washer is a spring k' , resting against the interior of a cap e^3 , secured to the box e by screws e^4 or other fastenings, and on 35 the shaft D is a washer k^2 , and back of this washer is a spring k^3 , also resting within the recess in the cap e^3 .

The balls are so fitted to the box that when 40 they are pressed into position, as shown in Figs. 6 and 8, they are confined between the rod and the shaft and the tapered walls of the box. When the rod F is moved forward in the direction of the arrow, Fig. 6, the pusher E will move with it, as the balls form a friction-coupling between the shaft and the box, and as the pusher moves forward it will slide 45 freely on the fixed shaft D, as the tendency of the balls will be to move from the cavities i' and clear of the walls of the socket e' of the box e ;

50 but on the return movement of the rod F the balls i^3 will hold the pusher rigidly to the fixed shaft D, while the rod F will slide freely in the box. Thus an intermittent forward feed is given to the pusher. When the

55 pusher reaches a certain point in its forward movement, it is automatically stopped by simply reducing the rod at f' , Fig. 2, so that the balls cannot be jammed between the rod and the walls of the socket e' , and consequently

60 there will be no forward movement of the pusher. In order to return the pusher to the opposite end of the casing to which it has been fed forward, I provide a push-bolt M, Fig. 10, which rests back of the carrier I and

65 when pushed will force it out of the sockets e' e^2 , so as to free the balls, and the pusher is then free to be moved to any point desired.

The springs K' K^3 return the carrier and bolt as soon as released.

In some instances I may use a cross-bolt M', 70 Fig. 12, having a beveled portion m resting back of the carrier, so that when the bolt is pushed in it will force the carrier out of the sockets. A spring m' will return the bolt as soon as released. 75

Thus it will be seen that I provide feed mechanism that can be adjusted to intermittently feed the pusher forward, and the machine can be set so that the food can be cut to any thickness, and I provide a simple friction feed mechanism and a simple method of adjusting the parts. Furthermore, I dispense with the long knife-shaft of the machine, using a short shaft, which is not in the way and which can be adjusted longitudinally, so as 80 to adjust the knife toward and from the cutting-face of the machine. 85

I claim as my invention—

1. The combination in a machine for slicing food, of a frame, a trough projecting rearwardly therefrom, a shaft shorter than said trough having one end supported in a bearing in said frame, an arm supported on the frame and providing a bearing for the other end of the shaft, a knife on the shaft on the outside of the frame, a cam also on the shaft, between the two bearings, a lever actuated by the cam, a pusher in the trough, a feed-rod connected to said lever, and frictional gripping mechanism between it and said rod whereby the pusher will be intermittently fed forward when the shaft is rotated, substantially as described. 95

2. The combination of a frame, a shaft mounted thereon, a knife carried by the shaft, 100 a cam also on the shaft, a lever pivoted to the frame and constructed to be actuated by the cam, a feed-rod connected to the lever, a fixed shaft, a pusher having a box with a tapered socket, a carrier in the said socket through which pass the feed and the fixed rod, balls in the socket and a spring constructed to keep the same therein, the balls and socket being 105 constructed so that the pusher is fed forward when the knife is rotated, substantially as 110 described.

3. The combination of a frame, a trough mounted thereon, a shaft on the frame, a knife and a cam on said shaft, a pivoted lever actuated by the cam, a feed-rod engaged 115 by the pivoted lever, a fixed shaft at the side of the trough, a pusher in the trough operative on the feed-rod and on the fixed shaft, the said pusher having a box in which are sockets, one of these being at the feed-rod 120 and the other being at the fixed shaft, a carrier in the sockets through which pass the fixed shaft and the feed-rod, balls also in the sockets and springs constructed to act against said balls, the whole acting to intermittently 125 feed forward the pusher when the feed-rod is reciprocated, substantially as described. 130

4. The combination of a trough, cutting mechanism, a fixed shaft at the side of the

trough, a rod paralleling the shaft, a pusher adapted to the rod and to the shaft, means for intermittently reciprocating the rod, sockets in the pusher, a carrier having portions adapted to the sockets and through which pass the shaft and rod, balls mounted between the carrier and the sockets, a spring back of the carrier, and means for forcing the carrier out of the socket so as to throw the friction mechanism out of gear, substantially as described.

5. The combination of a trough, cutting mechanism, a fixed shaft at the side of the trough, a rod paralleling the shaft, a pusher adapted to the rod and to the shaft, means for intermittently reciprocating the rod, sock-

ets in the pusher, a carrier having portions adapted to the sockets and through which pass the shaft and rod, balls mounted between the carrier and the sockets, springs back of the carrier, and a push-bolt mounted in the 20 pusher and resting against the front of the carrier, substantially as described.

In testimony whereof I have signed my name to this specification in the presence of two subscribing witnesses.

JOSEPH FELLOWS.
